UNITED STATES PATENT OFFICE.

R. H. FISHER, OF WEST MERIDEN, CONNECTICUT, ASSIGNOR TO THE BEAVER FALLS CUTLERY COMPANY, OF BEAVER FALLS, PENNSYLVANIA.

IMPROVEMENT IN CUTLERY.

Specification forming part of Letters Patent No. 79,061, dated June 23, 1868.

To all whom it may concern:

Be it known that I, R. H. FISHER, of West Meriden, New Haven county, Connecticut, have invented new and Improved Table-Cutlery; and I do hereby declare that the following is a full, clear, and exact description thereof, which will enable others skilled in the art to make and use the same, reference being had to the accompanying drawings, forming a part of this specification, in which—

Figure 1 represents a side view, partly in section, of my invention. Fig. 2 is an edge view of the same.

Similar letters of reference indicate corresponding parts.

The object of this invention is to so construct the tangs of knives and forks that the same can be held in the handle without the use of pins or other fastening devices, and that the outside of the handle will have a pleasing smooth appearance.

The invention consists in the use of a bifurcated or split tang, which is formed at the end of the blade in such a manner that the outer edges of the two tines or prongs will be flush with the handle. The ends of the prongs are bent in, so as to have a firm hold in the wooden or other handle. The bolster is fitted into recesses formed in the edges of the tangs, so as also to be flush with the edges of the handle and tangs.

A represents the blade of a knife.

B is the tang, which consists of two prongs *a a*, as is clearly shown in Fig. 1. The length of these prongs can be varied at pleasure, so that they be as long as the handle C or shorter than the same, as may be desired. The ends of the prongs *a* are bent in, so as to form hooks *c c*, whereby the handle C is firmly held and clamped. Recesses *b b* are formed in the edges of the tang B close to the end of the blade for receiving the metal bolster D. This bolster is made of one piece of metal, so as to surround the whole upper end of the han-

dle. It is firmly held between the shoulders formed by cutting the recesses into the edges of the tang. When the ends of the prongs *a* are bent in or made hook-shaped, the bolster is held firmly in position, as well as the tang, without requiring any other fastening devices; but when these hooks *c* are not formed on the ends of the prongs, the bolster is secured in the handle by a rivet or pin *d*, which passes through the bolster and handle and between the prongs *a a*, as is clearly shown in the drawings. The whole blade is then secured and held by means of the bolster, which, fitting between the shoulders of the recesses *b*, prevents the moving of the blade or tang.

It will be seen that a knife or fork, when constructed as described, is stronger and easier made than any other kind now in use, it being so arranged as to consist of three pieces only—viz., the blade and tang, the bolster, and handle.

Having thus described my invention, I claim as new and desire to secure by Letters Patent—

1. The bifurcated tang B, provided with hooks *c c*, fitting into the recesses in the handle C and secured in position by means of the bolster D, fitting into the recesses *b b* and over the end of the handle, as herein shown and described.

2. Securing the bifurcated tang B to the handle C by compressing the arms *a a* and slipping the bolster D into the recesses *b b*, as herein shown and described.

3. Securing the bolster D to the handle by means of the rivet *d*, passing through the handle between the arms *a a* of the tang, substantially as herein shown and described.

R. H. FISHER.
